UNITED STATES PATENT OFFICE.

TOLBERT LANSTON, OF WASHINGTON, DISTRICT OF COLUMBIA, ASSIGNOR,
BY DIRECT AND MESNE ASSIGNMENTS, TO THE LANSTON TYPE MACHINE
COMPANY, OF SAME PLACE.

TYPE FORMING AND COMPOSING MACHINE.

SPECIFICATION forming part of Letters Patent No. 364,525, dated June 7, 1887.

Application filed September 30, 1885. Serial No. 172,671. (No model.)

To all whom it may concern:

Be it known that I, TOLBERT LANSTON, of Washington, in the District of Columbia, have invented certain new and useful Improvements in Type Forming and Composing Machines; and I do hereby declare the following to be a full, clear, and exact description of the same, reference being had to the accompanying drawings, forming a part of this specification, and to the figures and letters of reference marked thereon.

While astonishing progress has been made in those branches of the art of printing which relate to the taking of impressions and to the folding and delivery of the matter printed, but comparatively little practical advance has been made in that department which relates particularly to the setting up and justification of the lines from which the impressions are to be taken.

Type setting machines of more or less efficiency, it is true, have been employed to assemble the types; but, even where such machines have been successfully used, it has always been found necessary to subject each line of composition to a process of justification involving usually the introduction by suitable mechanism, or by hand, of additional spaces, or of the substitution of wide for narrow spaces, and vice versa, much the same as in the case of matter set up by hand.

Machines have also been constructed with a view to the production of solid lines of justified composition; but even in such machines the justification of the lines is only secured by justifying the dies or molds which produce them, and this justifying operation is performed in the ordinary manner above referred to.

My invention is a wide departure from these previous methods, and proceeds upon a principle which I believe to be radically new.

Instead of producing a line of composition and then justifying it, I form my types for a given line in such manner as to cause them, when assembled, to form a complete justified line ready for printing direct, or for making an impression for stereotype or electrotype purposes, without further manipulation.

In attempting to supplant by machinery the ancient process of setting type by hand, the advantages to be derived from copying as many of the conditions of such hand-set type as possible is manifest. By so doing the mechanical products will be in harmony with all the other conditions of the art of printing as now practiced, will involve no departure from its usages, and will permit the same method of correction of errors, interpolations, shifting of matter, &c., as are now in vogue.

It is well known that in ordinary composition, where common type is used, it rarely ever happens that a series of words uniformly and regularly spaced exactly fill a line of given length, the rule being that a space of greater or less length is left at the end of the line, which must be filled up or absorbed in the process of justification. Now, since it is apparent that in every case this unoccupied space at the end of the line must bear a certain relation to the part of the line filled by the characters, or, in other words, represent a certain percentage of the combined width of such characters, it follows that if there be added to the normal width of the body of each of the assembled types a percentage of increase corresponding to the percentage which said unoccupied space represents to the occupied space the line composed of types so formed will be rendered self-justifying. To illustrate this, suppose the unoccupied space in a line required to be taken up by justification represented one per cent. of the part of the line filled by type of the normal width. The addition of one per cent. to the normal width of the body of each of such assembled type would cause this space to be taken up or absorbed, one per cent. addition to the width of each section or part of the assembled type being equal to one per cent. of the whole aggregated width of said type. Instead of thus adding to each type a certain percentage of the width thereof, the same result can be accomplished either by apportioning the unoccupied space in the line equally among all the types therein, and thus adding to all the types a certain uniform and definite increase in width—say a one five-hundredth of an inch to

each—or by apportioning the unoccupied space in the line equally among the space-types between words contained therein by adding an equal amount of increase to the normal width of each of such space's value.

5 In carrying out my invention I preferably employ, first, two independent record strips having perforations punched in them, indicating by their position the several characters that are to be employed in the production of a line or lines of printed matter, and one of them having in addition other perforations indicating the percentage of increase required in the normal widths of the types that are to compose each line, or the fixed amount of increase to be added to each of such types, or to the space-types between words only, as the case may be; and, secondly, a machine co-operating with said record-strips for making the 10 types in the desired order and of the proper width in conformity to the scoring of the strips, and assembling said types in justified lines in suitable galleys or forms.

15 The two record-strips are preferably made of ribbons of paper, and are preferably scored by means of special devices, which will form the subject-matter of a separate application for Letters Patent to be filed by me.

20 My method of scoring, whatever be the means employed, deals with the type with reference, first, to their normal space value when in the line, and, secondly, to their increased or justifying value. In punching the ribbons the normal value of the characters recorded is 25 measured on a scale, and when the last syllable which can be placed in a line has been recorded the scale indicates the amount of space in the line yet unfilled and the percentage which said unfilled space represents to the filled space.

30 In accordance with this showing a puncture is made in one of the ribbons at such a point as will record the particular percentage of deficiency required to be added to each of the types of the line. To enable, then, the machine which forms the type to so adjust itself as to increase the space value of the types made for a particular line above the normal in a degree necessary to thus make the line self-justifying, the record-perforations in the ribbons or 35 strips are brought into use in the reverse order in which they are made—that is to say, the last character in the last line of the article or subject to be printed is the first to be made. In this way the perforation which indicates 40 the degree above the normal to which the types in the line are to be increased as to space value is first brought into action and adjusts the machine for the production of the whole line, and the next succeeding percentage, perforation in 45 like manner sets the machine for the next line, and so on.

50 The principles involved in the formation of self-justifying lines or type in accordance with my invention is of course susceptible of being embodied in and carried out by various forms of machines; but the form of machine which I prefer to employ embraces, first, a series of

dies, as many in number as there are characters to be used; secondly, mechanism controlled by the scoring of both record-strips for centering in order, and preferably one at a time, the dies beneath a plunger or other instrumentality for operating said dies; thirdly, mechanism set in operation by the scoring of both the record-strips adapted to cause the centered dies to form, one after another, types of normal thickness; fourthly, mechanism set in operation by the scoring of one strip only for adjusting the type-forming mechanism so as to cause it to form types for a given line of a space value sufficiently increased above the normal to cause them, when assembled, to produce a self-justified line; fifthly, mechanism by the operation of which the type-forming mechanism is caused to increase the space value of the spaces between words sufficiently to produce justified lines, instead of being caused to increase the space value of all the types of the line; sixthly, mechanism for ejecting the completed type and preventing them from turning, and, lastly, mechanism for assembling the types in the form of justified lines in a galley and for advancing the galley properly as the lines are one after the other completed. These several mechanisms may be said to be divided into two main groups, by one of which is accomplished the selection of the particular characters or types to be made and the manipulation of the machine to suit the constantly-varying widths of said types, and by the other of which the types are made and set up in justified lines in accordance with the conditions prescribed by the first group. The first-named or regulating group of mechanism is also divided into two subdivisions, each of which has dual functions to perform, as will be herein-after referred to.

55 By preference I construct the frame work in the form of a right angle, and, looking from the inner side toward the corner or angle, I, for convenience in description, term that portion lying to the right the "right-hand side" of the machine and that lying to the left the "left-hand side" of the machine.

At the corner or angle of the machine is located a vertical driving-shaft driven by a belt and pulley from any suitable source of power. Connected to this shaft is a compound crank, or a crank having two wrists, and to each end of this crank is connected a pitman, which is jointed at its opposite end to a carriage adapted to slide back and forth upon guides on the right or left side of the machine, as the case may be. This compound crank is so arranged as to cause both the right-hand and left-hand carriages to be moved out or in upon their respective guides simultaneously. The inner end of each of the carriages is provided with a series of horizontal compartments or shelves of a number which is the square root of the number of characters that are to be used. In the present machine there are fourteen of these shelves; but the number is a matter purely arbitrary, and may be varied at pleasure. To

the outer end of each of said sliding carriages is hung a vertically-swinging arm, which has a longitudinal groove or guide that is adapted to receive and guide the outer end of one arm 5 of a bell-crank lever, which is pivoted to a stationary part of the frame-work. This connection is such that when the swinging arm is vibrated up from its normal position it will vibrate the bell-crank lever and present the 10 groove or guide in which its said arm works opposite one or the other of the compartments or shelves of the head of the sliding frame, so that as the sliding frame is advanced the said lever-arm will pass out from its groove in the 15 swinging arm and enter the corresponding shelf or compartment of the sliding frame and be kept therein until a reverse movement of the parts takes place. While so entered in said shelf the said arm of the bell-crank lever 20 rides upon a dead-level, and the bell-crank lever is thus kept motionless.

The lower arms of the bell-crank levers are connected by means of pitmen to the die-centering devices. The dies are in number equal 25 to the square of the number of shelves employed, and for this particular machine are one hundred and ninety-six in number, and are arranged in a suitable frame or carrier in the form of a square with fourteen dies on a 30 side. They represent all the characters that are required for use, and are classified in fourteen different lines, according to their width or space value. Such distribution of line values has relation to the right-hand side of the machine only, and when the bell-crank lever on the right-hand side of the machine is given an amount of vertical movement sufficient to cause 35 its upper arm to pass into the second shelf or compartment, the first line of dies in the square 40 is brought to the centering-point, while the movement of such bell-crank lever to the third shelf and the entry of its arm in said shelf would cause the second line in the square to be brought over the centering-point, and so on 45 progressively to the last or fourteenth line, each movement of the bell-crank indicating that a type of a particular space value is wanted and the line of types of the desired space value have been brought respectively to 50 the centering-point. Each die has the character which it represents formed on its lower end in either intaglio or relief, as desired, and each one is provided with a spring which operates to return it to normal position after it 55 has been depressed to form a character.

The frame in which the dies are supported is arranged within two oblong slides or carriers, which are adapted to be reciprocated back and forth at substantially right angles to 60 each other, one of said slides being actuated by the bell-crank lever at the right-hand side of the machine and the other by the bell-crank lever at the left-hand side of the machine. Above the dies is arranged a vertically-operating plunger, by which the dies are one after the other depressed, as occasion requires. From the manner in which the frame holding

the square of dies is controlled by these two slides or carriers, any desired die is enabled to be instantly brought or centered beneath 70 the co-operating plunger. For instance, if the fifth die from the left in the second horizontal line of the square of dies is desired to be centered under the plunger, it is only necessary that the bell-crank lever of the right-hand side of the machine should be given a movement sufficient to bring the second series 75 of characters into line with the plunger, and that the bell-crank lever of the left-hand side of the machine should be given a sufficient movement to bring the fifth cross-series of characters also into line with the plunger, and the desired centering operation will be automatically accomplished.

The throw of the bell-crank levers of course 80 depends upon the vertical motion that is given to the swinging arms to which they are connected, and the amount of vertical motion given said swinging arms in turn depends upon the engagement of one or the other of a 85 series of pins with a curved slot on the inner face of said arms. These pins are adapted to be projected by the operation of electro-magnets controlled by the scored record-strips, and accordingly as one or the other of said pins is 90 thrown out the swinging arm will be caused to rise more or less. That this may be readily understood, it will be necessary to state that co-operating with each of the record-strips is 95 a series of contact-fingers arranged alongside 100 each other crosswise of the strip, and each one of which is adapted to make contact through the strip, and thereby energize its corresponding pin-projecting magnet when the perforation in the strip passes beneath it.

The perforations are made in the strip in different longitudinal lines and at such distances apart progressively as to prevent contact being made through any two perforations at once.

Since the centering of any given die beneath the plunger which is to depress it depends upon the operation of both the slides or carriers which control the dies, and since the amount of motion required to be given one of 115 said slides or carriers may vary considerably from that required to be given the other one, it follows that the two record-strips which are to primarily control the actuation of the two die-centering slides must be perforated differently. For example, to effect the depression 120 of the die in the case before supposed, the right-hand strip will have to be punched so as to cause the projection of the pin that will produce an amount of movement of the swinging arm sufficient to throw the bell-crank lever in a manner to cause one slide to bring the second series of dies in line with the plunger, while the left-hand strip will have to be punched in a manner to cause the other slide 125 or carrier to bring the fifth cross series of dies into line.

Mechanism is provided for feeding the two strips simultaneously and uniformly, and the

result is that the appropriate perforations in the two ribbons permit the contact arms to operate simultaneously on both sides of the machine, and to cause the appropriate pins to be projected and the proper motion to be thereby given the vertically-swinging arms, and thus effect, through the bell-crank levers and connections, the simultaneous movement of the two centering slides or carriers to the extent which is necessary for them to respectively move in order to bring the proper die under the plunger.

The material from which the types are made may be of lead, composition metal, paper, 15 papier-maché, or, in fact, any material that will receive and retain an impression, and permit of a stereotype or electro-type being prepared from it, though I by preference use lead. The material, whatever it may be, is fed by suitable 20 feeding mechanism, in the form of a strip or bar, into a matrix or compressing-box that is located beneath the plunger which is to depress the centered die. While the metal is being fed into said compression-box the die is 25 depressed by the plunger above it, and brought down and firmly seated over the compression-box, its end, bearing the character to be formed, constituting the top of said compression-box. This done, a plunger adapted to snugly fit the 30 compression-box, and to work laterally in and out of one end of the same, advances, cuts off from the metal strip a section of sufficient width to form the desired type, and then compresses said cut-off portion in the box sufficiently to cause it to conform accurately to the 35 interior of said box, and be thereby formed into a completed compressed type. After the formation of the type, the die returns automatically to its normal position, the type is 40 ejected from the compression-box, and passes thence down through a throat or channel until its lower end reaches a suitable support, from whence it is automatically pushed laterally into a galley or form prepared to receive it. 45 Each completed type is in turn pushed up against its immediate predecessor, and all are advanced until the line is completed, when the galley is automatically shifted so as to receive the types for the next line, and so on. 50 One of the subdivisions of the regulating-group of mechanism, hereinbefore referred to, is located substantially on the right-hand side of the machine, and its dual functions, to which reference has also been made, consists, first, 55 in aiding the die-centering operation, and, secondly, in a function peculiar to itself—namely, that of controlling all of the regulating devices for making type of normal size. The other subdivision of the regulating group of mechanism is found on the left-hand side of the machine, and its dual function consists, first, in also aiding in the die-centering operation, and, secondly, in a function likewise peculiar to itself—namely, that of regulating the increase in the normal width or space value of 65 the types, so essential to the carrying out of

my improved system of forming justified lines of type.

The motions of the vertically-swinging arms, which play such important parts in the die-centering operation, are availed of in carrying out the separate functions of the two subdivisions of the machine. To the swinging arm on the right-hand side of the machine is jointed a longitudinally-slotted connecting-rod 7 that bears a pin or stud on its lower end, which engages with a curved or segmental slot in a vibrating lever whose extent of movement operates to control the feed of the type-metal strip as well as the stroke of the plunger that 8 cuts off and compresses the type, and the width of the throat through which the completed type passes on its way to the galley. So long as the normal position of the pin on the end of the said slotted connecting-rod in 8 the curved slot of the vibrating lever is maintained all the type that are made will be of normal size—that is to say, not all of one width or space value, but each of its own proper width or space value. Where it is necessary, however, to increase the normal width or space value of each type a percentage sufficient to absorb the space required to be filled by justification, a rod operated immediately from the swinging arm of the left-hand or justifying 9 side of the machine, and having a pin which enters the slot of the said vertically-slotted rod, causes said last-named rod to be shifted in the segmental slot of the vibratory lever, and thus increase the throw of said vibratory lever sufficiently to effect the feed of a greater amount of the metal strip into the compression-box and a corresponding shortening of the cutting and compressing plunger and a proportionate widening of the discharge-throat.

In regard to the details of the mechanism employed to cause the left-hand side of the machine to thus set the right-hand side for the formation of a given line of types, it is not necessary at this point to refer, further than to state that the motion of the vertically-swinging arm of the left-hand side is availed of in this operation, and that the amount of motion given said arm, and consequently the amount of increase in the normal width or space value of the types, is dependent upon the particular electro-magnetically-controlled pin that is projected in response to the corresponding justifying perforations in the scored record-strip for that side of the machine.

The same justifying mechanism which operates to increase the width or space value of all the types by adding to each a percentage of its normal value can, with slight modifications, be caused to justify on the other plans hereinbefore referred to—to wit, that of increasing the normal width of the spaces between words in the proportions necessary, and that of adding to the width of each type an equal amount of increase. The same principle is involved in all the methods, since it makes little difference whether the normal width or

space value of all or only a portion of the types is increased so long as the proper justification of the line is effected, the gist of this part of my invention being the production for a given line of types which, when assembled, will produce a justified line having equal spaces between the words.

It is obvious that instead of perforating the record-strips they may be rendered conductive at the points desired, so as to pass a current of electricity and thus effect the operation of the electro-magnets which control the pins; but the perforations will probably be found preferable, as with them more certainty of operation will be insured.

Compressed air may also be used for actuating the guide-pins in lieu of the electro-magnets, if preferred, and a mechanism embodying this idea is described hereinafter as a modification falling within the limits of my invention.

I will now proceed to a description of the machine in detail; reference being had to the accompanying drawings, in which--

25 Figure 1 is a top plan view of the entire machine. Fig. 2 is an elevation of the shelves or compartments of one of the sliding carriages, looking from the inner side. Fig. 3 is a similar view of the same, looking from the outer side. Fig. 4 is a side elevation of the right-hand side of the machine, looking in the direction indicated by the arrows No. 1 on Fig. 1. Fig. 5 is an elevation of the left-hand side of the machine, looking in the direction indicated by the arrow No. 2 in Fig. 1. Fig. 6 is an elevation of the opposite side of the left-hand portion of the machine, looking in the direction indicated by the arrow No. 3 in Fig. 1. Fig. 6^a is a detail view of the means for throwing the strip-feeding mechanism in or out of operation. Fig. 6^b is a detail view showing the relative arrangement of the shafts I^o and E^o. Fig. 6^c is a sectional view on line 21-21, Fig. 6^d. Fig. 7 is an enlarged sectional elevation taken on the line z z, Fig. 1. Fig. 7^a is a diagram illustrating the number and relative positions of the cams on the main driving-shaft. Fig. 8 is a sectional view taken on the line y y of Fig. 6. Fig. 9 is an enlarged view of the contact-fingers and their connections and the record strip with which they co-operate. Fig. 9^f is a view of a record-strip in which pieces of conducting material are employed instead of perforations for co-operating with the contact-fingers. Figs. 9^a and 9^b are respectively longitudinal and cross-sectional views of the rollers between and by which the record-strips are fed. Figs. 9^c and 9^d are detail views of a portion of the mechanism which throws the strip-feeding devices into and out of operation. Fig. 9^e is a view of the two record-strips. Fig. 10 is a top plan view of the die-carrier and the frames by which it is held and adjusted, and also of a portion of the galley in which the types are assembled as fast as made. Fig. 11 is a sectional view taken on the line x x of Fig. 10. Fig. 11^a is a de-

tached view of the cam which actuates the die-plunger. Fig. 12 is a view of one of the dies detached. Fig. 13 is a bottom plan view of the plunger which depresses the dies or type when centered, and which is shown in sectional view in Fig. 11. Fig. 14 is a sectional view of the type-forming matrix and of the means for feeding the metal strip into the same. Fig. 14^a is a bottom plan view of the die-frame. Fig. 15 is a sectional view taken on the line v v, Fig. 10. Fig. 16 is a sectional view taken on the line u u, Fig. 4. Fig. 17 is a bottom view of the devices shown in Fig. 16. Fig. 18 is a sectional view taken on the line t t, Fig. 16. Fig. 19 is a top view of the pawl for actuating the galley. Fig. 19^a is a sectional view of the pawl-carrier. Fig. 20 is a sectional view of the pawl-carrier, taken on the line s s, Fig. 19. Fig. 21 is a similar view taken on the line r r of the same figure. Fig. 46 is a detail view of the cam on the sliding carriage which operates the record-strip-feeding mechanism in this last-mentioned modification. Figs. 47

and 48 are respectively a bottom plan and an edge view of one of the pins through which motion is communicated directly to the setting-pins in said modification.

5 *The main frame.*—As before stated, the main frame of the machine is constructed preferably in the general form of a right angle, as shown in Fig. 1. Nothing particular need be stated concerning it further than that it is of the requisite strength and rigidity, and is built with a view to conveniently receiving and supporting the several parts of the mechanism employed.

10 *The die-centering mechanism and dies.*—At the corner or angle of the main frame a vertical driving-shaft, B, is located, the same being driven by a belt applied to a driving-pulley, B'. To the upper end of this shaft is secured a cam-wheel, C, having a series of cams upon it, whose functions will be further explained, and secured to the cam-wheel is a compound crank, D, having two wrists, d^a and d^b . To the wrist d^a is connected a pitman, d' , which is jointed at the other end to a carriage, D⁴, that is adapted to slide back and forth on suitable guides, D³, on the right-hand side of the machine, and from the wrist d^b another pitman, D², in like manner extends to a similar carriage sliding on similar guides on the left-hand side of the machine. When the main driving-shaft is rotated, the arm D and first-described connections cause both of the sliding carriages to move out and in simultaneously upon their respective guides. The inner end of part D⁴ of each of the sliding carriages has a series of horizontal compartments or shelves of a number which is the square root of the total number of characters the machine is designed to produce. With the present machine the production of one hundred and ninety-six different characters is contemplated, and therefore fourteen shelves (lettered from d' to D¹⁴) are employed. A vertically-swinging arm, D⁷, is pivoted to the outer portion, D⁵, of each of the 15 sliding carriages, and at its upper side is provided with a channel or guide, D¹⁰, in which works a cross-pin, D⁹, on the outer end of the upper arm of a bell-crank lever, D⁸, pivoted to the stationary part of the machine at d^4 , as shown particularly in Figs. 1, 4, 5, and 8. In proportion as the swinging arms are vibrated upward the bell-crank levers are also vibrated, and the grooves or guides D¹⁰ are respectively presented in the plane of one or the other of the series of compartments or shelves d' D¹⁴ of the corresponding head of the sliding frame. Then as the said sliding frame advances the pin or cross-head D⁹ of each lever-arm leaves its respective groove or guide and enters one 20 of the shelves or compartments of the corresponding sliding frame, and is kept therein till a reverse movement of said frame and arm takes place. The means for determining the amount of swinging motion given the arms will be further explained.

To the lower arm of the bell-crank lever D⁸, on the right-hand side of the machine, is con-

nected a rod, D¹¹, that is also connected to one of the slides D¹⁴ of the die-centering mechanism, and the lower arm of the bell-crank lever, on the left-hand side of the machine, is connected by a similar rod, D¹², to the other movable slide, D¹⁵, of the die-centering mechanism.

The slides D¹⁴ D¹⁵ are adapted to move one above the other at right angles to each other, and are guided in their movements by a fixed frame, D¹³, as shown in Figs. 10 and 11.

The dies lettered D²⁰ are in number equal to the square of the number of shelves or compartments in the heads of the sliding carriages, being one hundred and ninety-six in number in this particular machine, and they are arranged in rows in the form of a square, with fourteen dies on a side. They represent all the characters that are desired to be used, and are disposed or classified in fourteen different series, according to their space value or width. Each die has the character which it represents formed in relief or intaglio on its lower end, and each die is located in a compartment, D²³, formed in the bottom D¹⁹ of a frame or case, D¹⁷, (shown in Figs. 11 and 14^a), and is provided with a spiral spring, D²¹, operating against a pin, D²², to bring it back to normal position after being depressed. The frame D¹⁷ is placed within another frame, D¹⁶, upon which the slides D¹⁴ and D¹⁵ directly act.

Above the dies is arranged the vertically-operating plunger B², which serves to depress the dies one after another as they are centered beneath it. This plunger is preferably located in the lower end of the main vertical driving-shaft, as shown in Figs. 7 and 11. It is normally held retracted by the operation of a spiral spring, B⁵, but is projected once during every revolution of the driving-shaft by the striking of a lateral beveled projection, B³, formed upon or secured to its lower end against a corresponding fixed actuating-cam, B⁶, secured to the frame of the machine, as shown in Figs. 11 and 13. Each time the plunger is thus projected it strikes and depresses a die if one happens to be centered beneath it, and if not it makes a dead-stroke. In Fig. 11 the die-frame is shown adjusted in the position which it occupies when a dead-stroke of the plunger is made.

The cam which co-operates with the plunger is preferably provided with a shank, B⁸, which extends up through an adjustable screw-threaded thimble, B¹⁰, screwed into a cross-piece, B⁹, of the main frame, and has a nut, B¹¹, which bears upon the upper end of said thimble. A spring, B¹², the resistance of which very much exceeds the compressive force necessary to be exerted in forming a type, is within the thimble and operates to project the cam outward. By this arrangement the cam can be so adjusted as to yield slightly at first when struck by the projection on the plunger, and thus obviate breakage and lessen wear, and when wear does result a

slight adjustment of the thimble will compensate for it. The tension of the spring is controlled by the nut B¹¹.

Since the throw of the bell-crank levers D⁸, that form part of the die-centering mechanism, depends upon the amount of vertical motion that is given the swinging arms D', by which they are operated, it becomes important next to consider the means whereby the motion of the swinging arms is controlled.

On the inner side of each of the swinging arms, near its bottom, is a groove, A²², (see Figs. 6 and 8,) which is substantially straight at its outer portion, but is curved throughout the rest of its length, as shown clearly in Fig. 6. A²⁰ is a series of pins, as many in number as there are compartments or shelves on the sliding carriages on the right and left hand side of the machine, and, like said shelves, represent the square root of the whole number of characters it is proposed to use. Each of these pins is arranged in a suitable socket or bearing, A²⁴, and is connected to a pivoted lever, A¹⁸, which bears at its free end the armature A¹⁷ of an electro-magnet, A¹⁶. All the pins are arranged in the plane of the entrance to the groove A²² of their respective swinging arm D', and when any one of them is projected it enters said groove as the carriage carrying the swinging arm advances, and causes said swinging arm to be moved up to a greater or less degree, depending entirely upon the location of the particular pin employed, the first pin of the series (beginning at the right, Fig. 6) causing the maximum movement of the arm, and the last pin the minimum movement of the same, all as will be readily understood. Whenever the electro-magnet corresponding to any particular pin is energized, that pin is projected into engagement with the arm, and when said magnet is demagnetized a spring, A¹⁹, retracts the pin and returns it to normal position.

The operation of the magnets, it will be remembered, is controlled by the perforated record-strips. These strips are shown in Fig. 9^c, that to the right representing the one which controls the pins on the right-hand side of the machine, and that on the left the one which controls the pins on the left-hand side of the machine. Each of the strips has perforations corresponding to the pins which it is desired shall be projected on its particular side of the machine.

Inasmuch as the mechanism for feeding the strips, and through them operating the electro-magnets, is the same on both sides of the machine, a description of one will suffice for both. It consists of a reel, A', (see Fig. 8,) upon which the strip is wound, two feeding-rolls, A⁷ and A⁸, between which the strip passes and by which it is withdrawn from the reel, a step-by-step mechanism for advancing the strip at regular intervals, a series of spring-pressed contact-fingers, A⁴, as many in number as there are magnets and pins to be operated, and a contact-bar, A³, in circuit with the elec-

tro-magnets, and with a suitable electric battery or other source of electrical energy. The reel is held by a pin, A², which permits of its being applied or removed at pleasure. One of the feeding-rolls is provided with teeth and the other with corresponding holes for receiving them, by which provision the record-strip, which is provided with a corresponding continuous line of perforations along each edge, is positively and certainly fed.

The spring-pressed contact-fingers are arranged alongside each other, and bear with their contact-points upon the strip whenever, as the strip is fed along, a perforation comes beneath the point of either of the fingers, said point passes through the strip and makes contact with the bar A³, thus closing the circuit through the corresponding magnet, and causing the appropriate pin to be projected. It is essential that at the completion of the inward movement of each of the sliding carriages the pin for causing the centering of the next die should be projected, and to accomplish this it is of course necessary that the record-strip should be advanced so as to bring the next succeeding perforation into play. Various means may be employed for accomplishing this result. For instance, as shown in Figs. 6, 6^a, and 8, I may mount upon the shaft of one of the feed-rolls a ratchet-wheel, A⁹, and arrange to co-operate therewith a spring-actuating pawl, A¹⁰, mounted upon a swinging arm or pawl-carrier, A¹¹, having connected to it a spring, A¹², for returning it to normal position, and also an actuating-rod, A¹³, which extends up through a tripping-lever, A¹⁴, as shown in Figs. 6^a and 8. This tripping-lever is supported in the stationary frame of the machine, and has upper and lower cylindrical bearing portions, A²⁵ A²⁶, which permit of its being moved vertically up and down and also of its being rocked laterally. It is further provided with a laterally-projecting arm, A²⁷, at one side, that is adapted, when properly adjusted, to engage with a cam, A¹⁵, on the sliding carriage, and with another arm, A²⁸, at the opposite side, to which is connected a rod, A²⁹, that extends to the lower end of a pivoted lever, A³⁰, which carries a weight, A³¹, at its upper end, as shown in Fig. 6. When the weighted lever is swung into the position indicated by the full lines in Fig. 6, the tripping-lever is turned into the position indicated in Figs. 8 and 9^a, and as the sliding carriage carrying the shifting-cam A¹³ moves outward the said cam strikes the arm A²⁷ and raises bodily the tripping-lever and the rod A¹³ thereto connected, thereby causing the pawl-carrier A¹¹ to be vibrated against the tension of the spring A¹² and its pawl A¹⁰ to engage the ratchet-wheel A⁹ and rotate the feed-rolls, so as to bring the next perforation in the record-strip under its corresponding contact-finger, and thus cause the next operating-pin to be set; but when, on the other hand, the said weighted lever is thrown back into the position indicated by the dotted lines in Fig. 6,

the arm A^{27} will be swung out of the path of the movable cam, and no feed of the record-strip will take place.

A second pawl, A^{28} , is applied to the ratchet-wheel A^9 , for the purpose of preventing any backward movement of the same, while the actuating-pawl A^{10} is being brought to first position by the tension of the spring A^{11} .

As explained in the introductory part of this specification, the centering of any particular die beneath the plunger depends upon the conjoint action of both of the record-strips and the mechanism operated thereby on both sides of the machine. It is therefore essential that the feeding mechanism on both sides should be adjusted to operate simultaneously, or as nearly so as possible.

The record-strips are perforated differently, as shown in Fig. 9^e. This is necessary, since to center any particular die requires the co-operation of one perforation in each strip, that in one strip determining which particular line of the series in the square of dies is to be brought in line with the depressing-plunger, and that in the other strip indicating which particular line of the cross-series is to be so brought into line, as before explained.

The formation of type of normal size.—The principal instrumentalities employed in the formation of type of normal size are as follows, viz: a compression-box consisting of side walls, $E^{25} E^{26}$, a top slide, G^3 , having an anvil, G^{14} , a bottom slide, G^9 , rollers $E^{21} E^{22}$ for feeding to the compression-box the strip of metal from which the type-blanks are severed, and an automatically-adjustable plunger, E^{12} , working within said compression-box, and operating to cut off a portion of the metal strip and compress it into a type in said box.

The upper slide, G^{13} , is provided with an opening, G^{15} , adapted to receive the lower end of the centered die when depressed, and this opening is preferably slightly larger at the top than at the bottom, so as to insure the proper entry of the die should it in descending strike near one edge of the opening, instead of at the exact center of it. At the front, where the die reaches the limit of its descent, it accurately fits and closes the opening, with its end bearing the character substantially flush with the inner surface of the slide.

A back-and-forth motion is given the upper slide by means of the two cams $C^5 C^6$ on the main driving shaft operating upon an upper arm, g^4 , and a lower arm, g^5 , respectively, of a rock-shaft, G^{10} , connected by a crank, G^{11} , and a rod, G^{12} , to the said slide, as shown in Figs. 15 and 16.

The lower slide, G^9 , has an opening, G^{21} , through which the completed type is discharged from the compression-box, and a back-and-forth motion is given to it by means of two cams, $C^3 C^4$, which operate alternately upon two arms, $g^2 g^3$, of a rock-shaft, G^6 , connected through a crank, G^7 , and a rod, G^8 , to the said lower slide. The opening G^{21} is beneath the anvil G^{14} , attached to the upper

slide while the type is being formed and compressed.

The rolls $E^{21} E^{22}$, which feed the strip of metal into the compression-box, are provided, respectively, with pinions E^{20} and E^{23} , and a third pinion, E^{19} , on a shaft, E^{18} , meshes with the pinion E^{20} , and serves to operate the whole train when the shaft E^{18} is rotated. Secured to the said shaft E^{18} is a large ratchet-wheel, E^{17} , (see Fig. 18,) with which engages a series of pawls, E^{16} , carried by a vibratory arm or pawl-carrier, E^{15} . Motion is imparted to this vibratory pawl-carrier from a rock-shaft, E^5 , Figs. 4 and 6, through a rod, E^{14} , and an arm, E^{13} , and the rock-shaft is itself rocked by the movement of the vertically-swinging arm D^7 on the right-hand side of the machine, Fig. 4, communicated through a vertical slotted connecting-rod, E , and a bell-crank lever, E^3 , as shown in Fig. 4.

The plunger E^{12} has a screw-threaded shank, E^{11} , which engages with an adjustable nut, E^{10} , that is in turn connected by a ball-and-socket connection to a second screw-nut, G^4 , coupled to a screw-stem, G^3 , which is connected to an arm, G^2 , on a rock-shaft, G . A cam, C' , on the main driving shaft (see Figs. 7, 7^a) operates through an arm g , Fig. 6, secured to said rock-shaft and the described intermediate connections, to advance the plunger and cause it to first co-operate with the side wall E^{26} of the compression-box to cut off the portion of the metal strip fed to said box, and then to compress said cut-off portion, as will be presently explained.

The stroke of the plunger E^{12} is at all times uniform; but the length of said plunger is governed by the position of the adjustable nut E^{10} . Said nut has screwed to it a plate, E^9 , through an opening in which extends a pin or finger, E^8 , which projects from a rod or bar, E^7 , that is connected through an arm, E^6 , to the same rock-shaft E^5 through which the metal-strip feeding devices are operated. Accordingly as the rock-shaft is rocked more or less the nut E^{10} will be rotated more or less, and thus by retracting or projecting the shank of the plunger cause the head of the plunger to stop within a greater or less distance from the anvil, thus enlarging or lessening the size of the matrix in which the type is formed.

Each of the side walls, $E^{25} E^{26}$, of the compression-box consists of a block having an elongated slot, E^{27} , extending through it vertically, through which passes a bolt, E^{28} , as shown in Fig. 14. A wedge, E^{29} , operates to properly adjust said blocks longitudinally, and an adjusting screw, E^{30} , serves to properly secure them laterally.

In the operation of the machine, the centered die is first depressed and firmly seated in its opening in the upper slide, so as to form, in effect, a portion of the top of the compression-box. Then the strip of metal is fed by the operation of the feed-rolls and connections across the path of the plunger and cutter E^{12} . Whereupon the plunger advances, cuts off the

projecting portion of metal from the strip, and, continuing its forward movement, compresses and condenses such cut-off portion and causes it to conform to the interior of the compression-box, the result being the production of a completed compressed type bearing upon its end or face the character represented by the particular die employed.

Inasmuch as the devices for controlling the stroke of the plunger and the devices for controlling the feed of the metal strips are both operated from the vertically-swinging arm D^7 of the right-hand side of the machine through the above-described intermediate connections, and since the amount of movement of said vertically-swinging arm is dependent upon the space value of the character to be produced, and determines in conjunction with the corresponding swinging arm and connections on the left-hand side of the machine the particular die of that space value to be centered, it follows that as each die is centered and brought down into position in the compression-box the feeding devices will be operated so as to feed just the requisite amount of metal in front of the plunger, and the latter will be regulated in its length so as to form within the compression-box from said cut-off metal a type of the requisite density and of the proper normal space value. As soon as the type has been completed, the die withdraws from the upper slide, and both the upper and lower slides move forward together, carrying with them the type, the forward movement of the upper slide continuing till the type has been advanced to a point in vertical line with the discharge-throat F^6 , when it ceases and said upper slide begins to retreat, loosening the type from the anvil in so doing; but the lower slide moves forward till its opening G^2 also comes in line with said throat, when it is arrested, and the type being left without support drops down by its own gravity into the throat, and from thence is transferred to a galley, as will be hereinafter described.

In order that there may be no liability of the type sticking to the walls of the compression-box, and thus be prevented from dropping down through the throat F^6 , the wall E^2 is cut away, as shown at E^{10} , Fig. 14, to give sufficient clearance.

It may be mentioned, in passing, that by the provision of the adjustable nut G^4 the proper normal position of the die may be ascertained and preserved.

The formation of justifying type.—The next portion of the machine to be described in detail is that which relates particularly to the mechanism for forming some or all of the types of a line of abnormal space value, so as to produce a fully filled-out or justified line.

We have seen that in the production of type of the normal size or space value the length of the type-forming plunger at a given stroke and the amount of metal fed to the compression-box are dependent upon the extent of movement of the vertically-swinging arm D^7 of the

right-hand side of the machine, as communicated through the slotted vertical bar E , the bell-crank lever E^3 , and the other intermediate connections. Now, the upper arm of the bell-crank lever E^3 is provided with a curved or segmental slot, E^4 , in which works a pin, E^2 , on the slotted vertical bar E , and accordingly as the said pin is shifted in the slot of said bar more or less toward the inner end of the same the throw of said bell-crank will be more or less increased, and the result will be that the stroke of the type-forming plunger will be more or less shortened and the amount of metal strip fed to the compression-box correspondingly increased, thus causing the production of type of a width or space value greater than normal. This variation from the normal adjustment of the machine is effected by mechanism on the left-hand or justifying side of the machine, which I will now proceed to describe.

The upper arm of the lever D^8 on the left-hand side of the machine is formed with or has connected to it an arm, H , (see Fig. 26,) to which is jointed a short pitman or connecting-rod, H^1 , whose opposite end is in turn jointed to a sleeve or collar, H^2 , mounted upon a vertical shaft, H^3 , between a cam, H^4 , and a collar on said shaft, as shown in Figs. 25 and 26. This shaft H^3 is supported in bearings H^4 and H^5 , and is capable of being both rotated and moved vertically therein. Upon the left hand sliding carriage D^4 is secured an arm, H^6 , Fig. 5, which, when the carriage is moved outward in making a dead-stroke, is adapted to strike the cam H^4 and rock the shaft H^3 against the tension of a spring, H^8 , secured at one end to the arm H and at the other to the shaft itself, as shown in Fig. 26. Also, secured rigidly to the shaft H^3 is a collar, H^9 , having a stud or projection, H^9 , and a hooked arm, H^{10} , as shown in Fig. 27. The hooked arm H^{10} is adapted to engage with a hook, H^{11} , on the edge of a bar, H^{12} , when the shaft H^3 is rocked against the tension of the spring H^8 , while the stud H^9 is adapted to strike a lug, H^3 , on a sliding spring-projected pawl, H^{13} , and to disengage said pawl from one or the other of a series of ratchet-teeth, h , on the side of the before-mentioned bar H^{12} , when the shaft H^3 is rotated back by the action of the spring H^8 . The bar H^{12} is capable of a vertical motion, and is steadied and guided by means of a pin or screw, H^{15} , and a projecting rib, H^{16} , working in a vertical slot, H^{14} , in the frame-work of the machine, and also by a rod, H^{19} , secured to the frame and passing through a guide-opening in an extension, H^{20} , of said bar H^{12} , as shown in Figs. 25 to 30. Upon the rod H^{19} is arranged a spring, H^{18} , which is compressed when the bar H^{12} is raised by the shaft H^3 , but operates to pull down said bar when released from said shaft.

To the outside of the bar H^{12} is pivoted, at H^{16} , another bar, H^{12} , having teeth h on one of its edges, and guided at the bottom by means

of the flange H^{17} on the bar H^{11} , as shown in Fig. 25. This bar H^{12} performs no office in the system of justification first to be described, and is only referred to, in passing, that its illustration in the several figures of drawings, now being discussed may not tend to confusion.

Outside of the bars H^{11} H^{12} is a rod I , Fig. 25, the inner end of which is slotted at I' , and is supported by a pin, I^2 , which passes through said slot and into a stationary portion of the frame. Carried by this rod I is a laterally-projecting pin, I^3 , which is adjustable in and out and adapted to be secured by means of a set-screw, I^4 , Figs. 25, 29, 30, so as to project into the plane of the inclined edge of the bar H^{11} . The outer end of rod I is connected to an arm, I^5 , secured to a rock-shaft, I^6 , and said rock-shaft has connected to it a spring, I^5 , which operates to constantly keep the pin I^3 against the inclined edge of bar H^{11} , and has upon its end a gear-segment, I^7 , Figs. 6 and 7, which meshes with a similar gear-segment, I^8 , on a rock-shaft, I^9 . Rock-shaft I^9 has a bearing at one end in end of a rock-shaft, E^5 , before described, and carries an arm, I^{10} , to which is connected a rod, I^{11} , Figs. 6 and 7, bearing a pin, I^{12} , that projects within the slot of the vertical rod E , connected to the swinging arm D^2 of the right side of the machine, as shown in Fig. 4.

It is evident that accordingly as the rod I^{11} is retracted by the operation of the described instrumentalities its pin I^{12} will swing the rod E and cause its pin to approach nearer the inner end of the segmental slot E^4 of the lever E^3 , and thus effect the increase in the stroke of said lever E^3 , and consequently shorten the type-forming plunger and increase the feed of the metal strip, thereby causing the production of types of a width or space value greater than their normal space value.

The operation of this justifying mechanism will be understood from the following: When the machine is first set in motion, the tripping-levers, which control the mechanism for feeding the record-strips on both sides of the machine, are thrown back so as to clear their respective actuating-cams on the sliding carriages, and the result of this is that each of the carriages makes a dead-stroke and neither record-strip is fed. In making these dead-strokes the arms D^2 remain stationary, the pin on the lever D^8 entering into the lowest of the shelves or compartments D^4 . At the first dead-stroke on the left-hand or justifying side of the machine the arm H^6 on the carriage strikes the cam H^7 on the shaft H^3 and turns the shaft H^3 against the tension of the spring H^8 , thereby bringing the hooked arm H^{10} on said shaft beneath the hook H^{21} on the justifying-bar H^{11} , and causing the projection H^9 to retract or throw backward the pawl H^{13} out of engagement with the teeth h on the side of the bar H^{11} , with which it at the time is co-operating. During all succeeding dead-strokes the shaft and bar H^{11} remain connected in the manner described. As soon, however, as the tripping-

levers of the feeding mechanism are thrown into operation, the record-strips begin to be fed along and bring their perforations into play, to set the pins which control the motion of the arms D^2 . The record-strip employed on the left-hand side of the machine, it will be remembered, has, in addition to the perforations which co-operate with the perforations of the strip of the right-hand side to center the die, other perforations which represent the degree above the normal which the types of any given line are to be increased as to space value in order to produce justified lines, and the justifying-perforation for each line operates to properly set the machine before any of the types for that line are formed. Therefore, while both record-strips are advanced when the strip-feeding devices first operate, only the left-hand one brings into action a perforation—to wit, the justifying-perforation for setting the machine for the formation of the first line of type—the other strip presenting only a blank unpunctured portion. The effect of this is to produce a dead-stroke on the right-hand side of the machine and an operative stroke on the left-hand side. Now, the justifying-perforation is so located on the strip as to cause the projection of one or the other of the several pins which control the movement of the arm D^2 ; but accordingly as more or less increase in the normal width or space value of the types is required in order to produce a justified line, whichever pin said perforation causes to be projected that pin causes the arm D^2 , the bell-crank lever D^8 , connected to it, and the shaft H^3 to be vibrated correspondingly. Upon the upward movement of the shaft H^3 , the justifying-bar H^{11} , which is still in engagement with it, is also carried up, and its inclined or beveled edge operating upon the pin I^3 causes the rod I to be drawn backward, and to so operate upon the vertical connecting-rod E on the right-hand side of the machine, through the connections hereinbefore described, as to cause the pin E^2 on said rod to be shifted in the segmental slot E^4 of the arm E^3 to the point which will insure an amount of increase in the throw of said arm sufficient to so effect the length of the type-forming plunger and the feed of the metal strip to the compression-box as to secure the formation of the types of the particular space value which will render the line of types self-justifying. When the shaft H^3 descends in response to the downward movement of the arm D^2 , its hooked arm H^{10} disengages from the hook H^{21} of the bar H^{11} , and the spring H^8 turns it backward to first position, so as to bring the cam H^7 into position for being operated upon by the cam on the carriage at the next dead-stroke. The bar H^{11} does not descend with the shaft H^3 , but is held at the point to which it has been raised by the engagement of the spring-pawl H^{13} with one or the other of the ratchet-teeth on its side. During the formation of the types for the whole line the position of the bar H^{11} remains unchanged, and when a new line is to be formed

both record-strips again operate to produce dead-strokes on their respective sides. The effect of the dead-stroke on the left-hand side of the machine is to cause the cam on the carriage to again operate upon the cam H^7 and turn the shaft H^3 again forward, which causes the projection H^9 to retract and disengage the spring-pawl H^{12} from the bar H^{11} , and the hooked arm h^{10} to be again returned in position to catch under the hook H^{11} , and thus arrest the liberated bar H^{11} when impelled downward by the spring H^{10} . Following the dead-stroke on both sides of the machine is a dead-stroke on the right side and an operative stroke 15 on the left, the effect of which is to cause the justifying-bar to be again raised to proper position, and thus be held during the formation of the next line.

Justification by increasing the normal width or space value of the spaces between words.—The plan of justification which has just been described above involves the addition of a certain percentage to each type in the line; but by slight modifications and additions to the mechanism employed in carrying out said system justification may be effected by adding a percentage of increase to the spaces between words only. In carrying out this alternative system the following additional instrumentalities are employed, viz: a bar, H^{12} , Figs. 25 to 28, pivoted to the vertically-sliding bar H^{11} at H^{16} , and having one edge straight and the other edge inclined and provided with shoulders or teeth h' , as shown in Fig. 25, an arm, H^{23} , on the vertical shaft H^3 , and another projection, K , (indicated by dotted lines, Fig. 5,) similar to H^6 , applied to the head D^4 of the sliding frame opposite the shelf, representing spaces.

40 The pin I^3 is required to be shortened, so that it will project behind the bar H^{12} only, as shown in Fig. 30, instead of behind both bars H^{11} and H^{12} , as shown in Fig. 29, and the connecting-bar I^1 on the right-hand side of the machine is connected higher up on the lever I^0 , so as, with a given movement of said lever, to impart a longer vibration to the vertical rod E , which controls the type forming mechanism.

In operating upon this system, both sides of the machine first make dead-strokes, during which the vertical shaft H^3 on the left side is turned and caused to engage with the bar H^{11} by the action of the projection H^6 upon the cam H^7 , as before. On the next stroke a perforation in the left-hand record-strip representing the proportion of increase to be added to each of the spaces between words occurring in the line to be formed causes the projection of the appropriate pin, and the swinging arm D^8 is vibrated upward, carrying with it the shaft H^3 and connected bars H^{11} H^{12} . On the downward movement of the shaft H^3 the latter is vibrated by its spring back to first position, and the bars H^{11} H^{12} remain suspended by virtue of the engagement of the spring-pawl H^{12} with the bar H^{11} .

So long as types representing letters or other

characters are being formed the shaft H^3 reciprocates up and down in response to the movements of the arms D^7 and the lever D^8 , and the bar H^{12} remains stationary, neither device performing any part in such type-forming operation; but when a space is to be formed the perforation indicating it causes a pin to be projected, which so elevates the arm D^7 and shaft H^3 as to cause the projection K to strike the cam H^7 and partially rotate the said shaft, thereby causing the arm H^{23} to strike against the shoulder h' on the edge of the bar H^{12} that happens to be opposite, and to swing said bar and cause the requisite amount of motion to be given the rod I to effect the desired result.

It will of course be seen that, accordingly as the bar H^{12} is set high or low, the amount of swinging motion given said bar will be greater or less, because of the progressively-increasing length of the steps or shoulders engaged by the arm H^{23} , and the amount of increase in the width of the space over and above its normal width will be regulated accordingly. Before the justifying-perforation for the next line is fed along the machine makes a dead-stroke on both sides, and the projection H^6 , striking the cam H^7 , causes the projection H^9 to retract the spring-pawl and drop the shaft in position for again raising the bar H^{12} to the desired point.

The assembling of the completed type.—The completed type, as they are discharged from the compression-box, drop down through a throat, F^6 , onto a ledge, M , forming one of the guides or ways for the galley, and are transferred thence to the galley, one by one, by the operation of a laterally-moving bar or plunger, G^9 , upon the throat-piece F^6 . If the type-throat F^6 is made large enough to accommodate the largest-sized type, it is evident that it will be so much too large for the narrower types as to permit of their becoming turned in their passage through it. To guard against this turning of the type, I therefore provide means for automatically adjusting the size of the throat to correspond to the thickness of the particular type which is to pass through it—that is to say, I employ an adjustable throat-piece, F^6 , Figs. 15, 23, and 24, and connect to it a lever, F' , having upon its outer end a beveled portion, F^2 , with which co-operates an arm, F , on the rock-shaft E^5 , on the right-hand side of the machine. This rock-shaft, it will be remembered, constitutes one of the instrumentalities through which motion is communicated to the type-forming plunger and to the metal-strip-feeding devices, and therefore, accordingly as it is rocked more or less, it imparts, through the described connections, a corresponding motion to the movable throat-piece and creates a throat sufficiently large to pass the completed type formed on that stroke, without being large enough to permit of the turning of said type. At the lower end of the type-throat are located two flat springs, G^9 , having beveled projections at their outer ends, as shown in Fig. 17. As each completed type drops down the throat, it passes

between these springs, and is prevented by their beveled projections from falling forward toward the galley. When, however, the plunger G^{19} is advanced, it causes the throat-piece 5 F^3 , which is also between the springs, to push the type past the beveled projections and into the galley.

The galleys employed are indicated by the letter M , Figs. 11, 15, and 17. They are 10 adapted to rest and slide upon guides or ways $M' M'$, and each one carries a series of bars, G^{22} , of a height preferably about equal to half the height of the type formed, and of a width corresponding substantially to the width of a line of types, and also carries a series of thin partitions or steel leads, M^3 , between which the said bars G^{22} are laid, as shown in Fig. 11. As the first completed type is discharged from the throat into the galley, it passes in between 15 two of the leads or line spaces M^3 and pushes along the bar G^{22} therein a distance equal to its width, this operation being repeated till the line is formed, each succeeding type pushing along its predecessor and causing the bar 20 to retreat until it is finally discharged from the galley through a slot, G^{23} , as shown in Fig. 15. The types themselves are prevented from being ejected with the bar by means of an abutment, M^2 , against which they strike when 25 the line becomes full. After the completion of one line, the galley is automatically advanced sufficiently to enable the types for the next line to be assembled in the manner indicated between the next two leads. When one 30 galley is full, another is slid in right behind it, and in turn is filled without requiring any stoppage of the machine.

Each galley is preferably provided at its opposite ends with shoulders m and pins m' , 40 that are adapted to fit corresponding shoulders and pin-holes upon adjoining galleys, and thus operate to secure the galleys together with practically smooth joints. Other modes of connection may be adopted, if desired.

45 The motion of the justifying mechanism on the left-hand side of the machine is availed of to operate the mechanism for effecting the automatic advance of the galley. Such galley-advancing mechanism consists of a rock-shaft, 50 L^2 , adapted to be turned in one direction by the operation of a plate or arm, L , on the extension H^{20} of the vertically-moving justifying-bar H^1 upon an arm, L' , secured to said shaft, and in the opposite direction by means of a 55 spiral spring, L^3 , as shown in Figs. 25, 26, and 28. Rigidly secured to the outer end of said rock-shaft is an arm, L' , Figs. 15 and 22, which contains a spring-projected dog or pawl, L^0 , and bears a pin, l' , which works within 60 an inclined slot near the end of the part l^2 of an arm, L^6 , pivoted at l' to the stationary arm L^5 of an elongated sleeve, L^4 , mounted upon said shaft L^2 , and bolted or otherwise secured to the frame-work, as shown in Figs. 15 and 65 19. The other part, l^2 , of the arm L^6 has upon it a pin, l^6 , which works within a slot, l^6 , in another pawl, L^9 , located within the arm L^8 ,

also forming part of said sleeve L^4 . A partition or division plate, L^{13} , Figs. 19, 19^a, and 22, fits loosely upon the shaft, and is bolted to 70 the fixed arm L^8 , and separates the parts of said arm and the parts immediately connected to it from the movable arm L^7 and its connected parts. The two pawls L^{10} and L^9 are pitched reversely, and are adapted to engage, 75 respectively, with corresponding ratchet-bars, L^{12} and L^{11} , on the under side of the galley, as seen in Figs. 15 and 17.

The operation of this mechanism is as follows: Normally the pawl L^{10} is in engagement 80 with its ratchet-bar L^{12} , while the pawl L^9 is retracted, and when the justifying-bar H^1 is raised to the position required to effect the justification of the line of types about to be formed the plate L or its extension H^{20} strikes 85 the arm L' , and rocks the shaft L^2 in the direction indicated by the arrows, Figs. 25, 26, 15, and 17, against the tension of the spring L^3 . This rocking of the shaft swings the arm 90 L' fixed thereto, and causes the pawl L^{10} to operate against the face of one of the teeth of the ratchet-bar L^{12} , and the galley to be advanced so as to bring it in position for properly receiving the next succeeding line of types. While the arm L' is thus swinging with its 95 pawl in engagement with its ratchet-bar, the pin l^4 operates to depress the pivoted arm L^6 and to cause the pin l^6 to project the pawl L^9 into engagement with one of the teeth of the ratchet-bar L^{11} , thus arresting the galley and preventing it from racing. Upon the down-stroke of the justifying-bar, the spring L^3 on the shaft L^2 will rock the said shaft and cause the arm L' to be swung back in the opposite direction, during which motion the spring-pawl will yield as it passes over the back of the next tooth, and will spring down in front of said tooth, while the pawl L^9 will be gradually retracted, ready for the next operation. After the types have been assembled, they may be printed from direct, or a stereotype or electrotype may be taken from them, as preferred, by well-known processes.

Modifications of the mechanism for operating the setting-pins.—Instead of the vertically-swinging arms D^7 and their co-operating shelves or compartments on the sliding carriage, and the electro-magnetically-operated pins for determining the extent of movement of said swinging arms, I may employ the arrangement shown in Figs. 31 to 36, wherein compressed air or other fluid is employed to set the pins, and a vertically-sliding plate having grooves or guides on its side is adapted to co-operate with the pins and to impart the requisite amount of movement to the bell-crank levers, which communicate motion to the die-centering and type-forming mechanisms. Referring to said figures, O , Fig. 33, represents a sliding frame such as is employed on each side of the machine, and having imparted to it a reciprocating motion through a pitman, O' , connected to one wrist of the arm on the main driving-shaft, as in

the other form of machine. This sliding frame carries a vertically-movable plate, O^2 , which has on one side a series of grooves or guides, O^3 , corresponding to the number of setting-pins employed, and is provided upon the other side with a groove or guide, O^4 , in which works a roller, O^5 , on the end of the upper arm of the bell-crank lever D^8 , referred to in the machine proper. The plate O^2 is adapted to slide vertically, and is guided in its movements by grooved rollers O^6 . (Shown in Figs. 31 and 33.) The pins O^7 , Fig. 34, which co-operate with the grooves or guides O^3 on the plate O^2 , are arranged in vertical series, each one standing normally opposite the outer end of its respective groove or guide, as shown in Fig. 31. When either one of these pins is projected, it enters the adjoining groove or guide O^3 , and, as the sliding carriage bearing the plate O^2 is advanced, causes the plate O^2 to be raised vertically more or less, according to the pitch of said groove or guide, thereby imparting to the bell-crank lever D^8 a greater or less movement, and through the latter effecting the centering of the appropriate die and the formation of a type corresponding thereto.

Each of the grooves or guides is made horizontal near its extremities, as shown, the horizontal portion at its outer extremity being for the purpose of permitting the setting-pin to fully enter before engaging the pitched or inclined portion of the groove, and the horizontal portion at its inner extremity being for the purpose of holding the plate O^2 motionless at the time when it is desired that the bell-crank lever which is engaged with the opposite side of said plate should also be held motionless, so as not to disturb the die-centering devices during the operation of the type-compressing mechanism, said last-named horizontal portions of the grooves performing, in this respect, offices like those performed by the shelves or compartments on the sliding carriages of the main machine, hereinbefore described.

45 The devices for effecting the projection of the pins O^7 by means of the perforated record-strip in this modification are constructed as follows: Upon the main driving-shaft B is secured an eccentric, P , which imparts motion to through a rod, P' , to the piston of an oscillating air-compressing cylinder, P^2 , Fig. 33, and a cam-groove, P^3 , in a ring or plate, also connected to and revolving with the said main driving-shaft, operates to shift the valve P^4 , which controls the withdrawal of compressed air from the reservoir P^5 , connected to said air-compressor.

60 A pipe, P^6 , is connected to the air-reservoir P^5 through the valve P^4 , (shown in Figs. 32 and 33,) and has two branches, p^6 , which extend, respectively, to the right and left sides of the machine, and connect, respectively, to a chamber, P^7 , in which works a piston, P^8 , that has a stem, p^8 , encircled by a spring, P^9 , within said chamber, and connected outside of said chamber to a movable block or jaw, P^{10} , as shown in Fig. 36. This block or jaw P^{10}

has within it a longitudinal channel, P^{11} , and a series of smaller channels or passages, P^{12} , corresponding in number to the number of setting-pins employed, extending from its concave face P^{12} to said longitudinal channel. Cooperating with this movable block or jaw P^{10} is a stationary block or jaw, P^{14} , having a convex surface conforming to the concave surface of the movable block, and having a series of channels, P^{15} , corresponding in number and position to the small lateral channels P^{13} in the movable block. The longitudinal channel in the movable block, into which all the small channels of that block open, is in communication, through pipe P^{16} and the port P^{17} of the valve P^4 , with the air-reservoir, while each of the several channels or passages P^{15} in the stationary block or jaw is in communication, through one or the other of a series of pipes, P^{18} , with a cylinder, P^{19} , in which works as a piston one of the setting-pins, O^7 .

Between the movable block or jaw P^{10} and the stationary block or jaw P^{14} passes the perforated record-strip which controls primarily the operation of the setting-pins. This strip is unwound from a reel, P^{20} , located on one side of the said stationary and movable blocks, by the operation of two intermeshing feeding-cylinders, $P^{21} P^{22}$, on the other side of said block or jaws rotated by a pawl-and-ratchet device, P^{23} , actuated by means of a rod, P^{24} , and a cam, P^{25} , on the sliding carriage O . As the sliding carriage O reaches the limit of its inward movement, the cam P^{25} operates upon the rod P^{24} , and, through the described intermediate connections, causes the record-strip to be advanced sufficiently to bring one of the perforations $P^{13} P^{15}$ in the movable and stationary blocks or jaws P^{10} and P^{14} , respectively. As soon as this adjustment of the record-strip is accomplished the valve P^4 is shifted by the cam-groove P^3 so as to bring its port P^{26} into communication with the pipe P^6 , which admits compressed air into said pipe P^6 and causes the piston P^8 (see Fig. 36) to be projected forward against the tension of the spring P^9 , and the movable block or jaw P^{10} , connected to the stem of said piston, to be moved toward the stationary jaw P^{14} , thus tightly compressing the intervening record-strip. This accomplished, the further movement of the valve P^4 brings its port P^{17} into communication with the pipe P^{16} , and thereby permits compressed air to pass through said pipe into the longitudinal channel P^{11} of the movable block P^{10} , and from said channel out through the lateral passage or channel P^{13} , which is in line with the operative perforation of the record-strip, thence through the said perforation in the record-strip into the corresponding channel or passage, P^{15} , in the stationary block, and thence through the pipe P^{18} to the chamber or cylinder P^{19} , wherein is located the particular setting-pin corresponding to the aligned perforation of the record-strip. The air-pressure acting upon this setting-pin operates to

project the same into the groove or guide in the vertically-movable plate O^2 , and as the sliding carriage advances the plate O^2 is lifted so as to impart the proper amount of motion to the bell-crank lever D^8 . When the sliding carriage nears the end of its backward movement, its beveled or cam surface P^{27} , located within the groove or channel O^3 at the front thereof, strikes the end of the projected pin O^7 and forces it inward, while at the same time the valve P^4 is shifted so as to permit the compressed air in the cylinders P^7 and P^{10} to escape through the pipes connected thereto.

The withdrawal of the air-pressure from the piston P^8 in the cylinder P^7 permits the spring P^9 to assert itself and carry the piston back to normal position, thus causing the block or jaw P^{10} to be retracted sufficiently to release the record-strip, and to permit the feeding devices, which at this juncture become operative by reason of the engagement of the cam P^{25} with the rod P^{24} , to advance the record-strip so as to bring the next perforation into position for registering with the appropriate air-channels in the stationary and movable blocks or jaws, as will be readily understood.

It will be observed that the port P^{26} in the valve P^4 is about twice the area of the port P^{17} in said valve, so that full pressure may be admitted to the pipe P^6 , for the purpose of effecting the closure of the movable jaw P^{10} before communication between the air-reservoir and the pipe P^{16} is established through port P^{17} , and so that after communication has been established with said pipe P^{16} through said port P^{17} the port P^{26} will still remain open, so as to maintain the pressure in the cylinder P^7 .

I preferably apply a friction-sleeve, O^8 , to the end of each of the setting-pins, as shown in Fig. 34, in order to reduce the friction between the pins and the grooves or guides in the plate O^2 to the minimum.

In Figs. 43 to 48 I illustrate another modification of the means for actuating the setting-pins that are to control the movements of the vertically-swinging arms or the vertically-sliding plates on the sliding carriages. On the whole, this modification is preferable to either the plan which involves the use of electromagnetism or the plan in which compressed air figures, for the reason that it embraces only positively-acting mechanism, less liable to disarrangement and more certain in its operation than those employed in connection with the other plans referred to.

Referring to last-mentioned figures, U represents the setting-pins and U^8 the record strip. Each of the setting-pins is mounted so as to be capable of a longitudinal movement back and forth, and through each passes transversely a pin, U' , the shank of which is flattened, as shown at U^2 , Figs. 47 and 48, and is guided as the setting-pin is moved back and forth in a slot, U^3 , in the stationary part U^4 , as shown in Figs. 45, 47. U^5 represents a series of levers—as many in number as there are setting-pins. Each of these levers is pivoted

at U^6 , and one of its arms extends beneath one of the pins, U' , while the other one bears a finger or projection, U^7 , which is adapted to enter corresponding perforations in the record-strip U^8 , also shown in Fig. 45. A spring, U^9 , operates upon the lever to keep the finger normally depressed upon the record-strip.

U^{10} represents a sliding carriage such as is found on each side of the machine, and corresponding to the sliding carriage lettered D^5 in Figs. 5 and 26. Secured to this carriage is a bar, U^{11} , which has a longitudinal slot or guide, U^{12} , on its side, in which works the end of an arm, U^{13} , secured to a rock-shaft, U^{14} . For the greater part of its length the slot U^{12} is straight; but near its outer end it is inclined, as shown in Fig. 44. From this it results that while the carriage is moving through the greater part of its stroke the arm U^{13} remains motionless; but when the end of the outstroke is approached the said arm passes into the inclined portion of the slot, and is thereby depressed, thus causing the shaft U^{14} to be rocked. A reverse movement of the carriage rocks the shaft back to first position, where it remains during the remainder of the stroke in that direction.

Secured to the rock-shaft are two arms, U^{15} , which are connected at their lower ends by a bar, U^{16} , Figs. 43, 44, 45. Also secured to the rock-shaft are two other arms, U^{17} , which are in like manner connected at their ends by a bar, U^{18} . The record-strip U^8 passes from a drum, U^{19} , over a bed or block, U^{20} , and thence between a pair of feed-rolls, to one of which is secured a ratchet-wheel, U^{21} . Co-operating with this ratchet-wheel is a vibrating arm, U^{22} , carrying a pawl, U^{23} , and having connected to it a rod, U^{24} , the outer end of which has a cam projection, U^{25} , which stands normally in the path of a cam, U^{26} , on the sliding carriage, as shown in Figs. 45 and 46. As the sliding carriage nears the inner end of its stroke, the cam U^{26} strikes the projection U^{25} on the rod U^{24} , and, through the pawl-arm and other intermediate devices, causes the record-strip to be advanced, and to bring beneath the finger of one or the other of the levers U^5 a perforation. Whereupon the said finger drops into the said perforation, and, under the influence of the spring U^9 , the pin U' , corresponding to the lever actuated, is pressed upward. Then immediately at the commencement of the outward movement of the carriage the arm U^{13} enters the inclined portion of the slot U^{12} and vibrates the rock-shaft U^{14} in a manner to cause the bar U^{16} on the arm U^{15} to sweep forward, strike the head of the elevated pin U' , and carry said pin forward and with it the setting-pin through which it passes. During the remainder of the outward movement of the carriage, as well as during a greater portion of the inward movement of the same, the setting-pin referred to remains projected, by reason of the pressure of the bar U^{16} against its elevated actuating-pin U' , and the extended portion U^{30} of the said bar U^{16} projects over

all the other pins U' of the series and prevents any displacement of the same. As the end of the next inward movement is reached, however, the arm U^{12} is thrown in the opposite direction by the inclined portion of the slot U^{12} , which causes the bar U^{10} to swing out from contact with the elevated pin U' , and the bar U^{18} on the arm U^{17} to swing forward, strike the inclined portion U^{28} of pin U' , depress said pin, and then, by engagement with the shoulder U^{29} of the same, carry it back and with it the setting-pin to first position. The depression of the elevated pin U' of course causes all the levers U^5 to be tilted on their pivots, so as to withdraw the finger of the depressed lever from the perforation in the record-strip and lift all the remaining fingers from contact with the record-strip, so as to permit the feeding mechanism to advance the record-strip without any resistance from the fingers, and bring another perforation into play.

Above the levers U^5 , and between them and the rod U^4 of the strip-feeding mechanism, I arrange a pivoted bar, U^{32} , and to an extension of it I apply a gear-sector, U^{33} , which meshes with a corresponding sector, U^{34} , on an operating shaft, U^{35} . This shaft U^{35} bears a weighted arm, U^{36} . By shifting the weighted arm to one side of the shaft the pivoted bar U^{32} is brought into the position shown in dotted lines, Fig. 45, and operates to tilt all of the pivoted levers U^5 , so as to raise their points or fingers from the record-strip, as well as to lift the rod U^{24} of the strip-feeding mechanism out of the path of the actuating-cam projection U^{25} on the sliding carriage. By throwing the weighted arm on the other side of the shaft the said bar U^{32} permits the parts to assume their normal operative position.

It will of course be understood that a gear-segment similar to U^{31} is secured to the other end of the shaft U^{35} , for meshing with the duplicate mechanism on the other side of the machine, so that the shifting of the weighted arm will render the mechanism on both sides of the machine operative or inoperative simultaneously.

Modification of the justifying mechanism.—In Figs. 37 to 42 is represented a modification of the devices for effecting the formation of justified lines of type. By means of this modified form of mechanism not only can justification be effected by the addition to each character or type of a certain percentage of its own normal width, or by the proper increase in width only of the spaces between words, but also by the addition to the width of all the characters or types in a line a certain definite amount of increase, the same to each character or type, regardless of its normal width or space value.

Referring to the last-mentioned figures, I^6 represents a shaft corresponding to the one similarly lettered in Figs. 6 and 7, and which is adapted to be rocked in one direction through the agency of the connecting-rod I ,

pin I^3 , and bars H^{11} or H^{12} , Figs. 5 and 25, and in the opposite direction by means of a spring, I^{15} , applied to it, as shown in Fig. 7. This shaft has connected to it an arm, R , which is jointed to one end of a centrally-pivoted lever, R' , having connected to its opposite end a bar, R^2 , that is jointed by a swiveling connection, R^3 , to the shaft R^4 , located within a hollow rock-shaft, R^5 , mounted in fixed standards or bearings R^6 , as shown in Fig. 37.

The rock-shaft R^5 is adapted to be rocked by means of a lever-arm, R^8 , corresponding to the arm E^3 in Fig. 4, and, like said last-mentioned arm, receiving motion from the vertically-moving arm D^1 , on the right-hand side of the machine, and said rock-shaft is formed with a depending portion, R^7 , which is inclosed by a plate, R^8 , at the front and a longer plate, R^9 , at the rear, as shown in Figs. 37 and 39 to 41, the plate R^8 being secured to the plate R^9 by screws or other fastenings, as shown. A yoke, R^{10} , also incloses the part R^7 , and its upper ends are connected by a pin, R^{11} , bearing friction-roller R^{12} , working in a slot, R^{13} , in an arm, R^{14} , pivoted to a frame, R^{15} , and adapted to be secured at different angles by means of a segment, R^{16} , and suitable locking devices, as shown in Fig. 37. This frame R^{15} is connected to the longitudinally-moving shaft R^4 , by means of a screw, R^{17} , which passes down through a slot in the tubular rock-shaft R^5 . The lower end of the yoke R^{10} is connected by a link, R^{18} , to an arm, R^{19} , on a rock-shaft, R^{20} , which has its bearings in lugs on the plate R^9 , (shown in Fig. 40,) and bears at one end another arm, R^{21} , provided with a slot, R^{22} , through which passes a bolt, R^{23} , secured to a block, which is adapted to ride between vertical guides R^{24} , affixed to the standard R^6 . (Shown in Fig. 42.) The set-screw R^{25} serves, in connection with a nut, R^{26} , on the bolt R^{23} , to secure said bolt at any desired point of adjustment within the slot R^{22} . When desired, the yoke R^{10} may be connected to the plates R^8 and R^9 by bringing perforations R^{27} therein into line with corresponding perforations R^{28} in said plates and passing a pin through said perforations, as will be readily understood. The link R^{18} can also be disconnected from the arm R^{19} by the removal of the pin R^8 .

In an extension, R^{29} , at the lower end of the plate R^9 , are arranged two blocks, R^{30} R^{31} , rendered adjustable vertically by means of adjusting-screws R^{32} R^{33} , respectively, and having pin-bearings R^{34} R^{35} , respectively, that enter corresponding vertical grooves in connecting-rods R^{36} R^{37} , which lead, respectively, to the mechanism for regulating the increase of the stroke of the type-forming plunger above the normal and to the mechanism for regulating the feed of the metal strip to the compression-box. A laterally-extending arm, R^{38} , on the lower end of the plate R^9 , is adapted to operate upon the lever F' , which regulates the area of the throat through which the com-

pleted types pass on their way to the galley in precisely the same manner as said lever is operated upon by the arm F in Figs. 6 and 24.

When it is desired to produce justified lines 5 by the addition of a certain percentage to the width of each character, the pin I³, Fig. 25, upon the bar I is adjusted so as to engage with the beveled edge of the justifying-bar H¹¹, and upon the said bar H¹¹ being raised in the 10 manner hereinbefore described to the height required to effect the addition of the desired percentage, the shaft I⁶ will, through the instrumentality of the bar I, be rocked, so as to cause a movement of the arm R from the position 15 indicated by the dotted lines in Fig. 37 toward the position indicated by the full lines in said figure, which movement of the bar R will, through the operation of the centrally-pivoted lever R' and the bar R², cause the central shaft, R⁴, to be forced in longitudinally, and thereby cause the inclined slotted arm R¹¹ to force down more or less the yoke R¹⁰, and, through the operation of the link R¹⁸, arm R¹⁹, shaft R²⁰, and adjustable slotted arm R²¹, swing 20 the plates R⁸ R⁹ more or less out of vertical line, according to the amount of throw given the yoke R¹⁰ and the position of adjustment at which the pin R²³ is secured within the slot R²² of said arm R²¹. This preliminary adjustment 25 of the plates R⁸ R⁹ out of a vertical position causes the connections R³⁶ R³⁷ to be shifted, so as to set the plunger and the strip-feeding mechanism at the adjustment necessary to produce types having the proper percentage 30 of increase in width; and when, through the operation of the mechanism of the right-hand side of the machine communicated to the lever R⁸, the plates R⁸ R⁹ and their connections are vibrated back and forth, such 35 types will be produced. Before the next line of types is formed the mechanism is returned to normal position and reset according to the justification required for the new line.

In order to justify by adding to each type or 40 character an equal amount of increase in width, the only change required is the insertion of a pin through the perforations R²⁷ R²⁸, so as to connect the yoke R¹⁰ to the plates R⁸ R⁹, and the removal of the pin R⁸, so as to throw the 45 shaft R²⁰ and connections out of operation.

To justify by increasing the thickness of the spaces between words only, the only further change in the adjustment of the parts required is that the pin I³, Figs. 5, 25, and 30, be shifted 50 so as to co-operate with the justifying-bar H¹¹, instead of with the justifying-bar H¹¹, in the manner heretofore pointed out.

While I have not claimed, specifically, the several modifications of the devices for operating the setting-pins from the record-strip, nor the modification of the part upon which the setting-pins operate, and from which the type-forming devices are controlled, I do not abandon nor waive my right to do so, as I propose to cover said features in a division or 60 divisions of this application. Neither do I claim herein the several described methods or

processes of forming the types and lines of matter, nor the type, nor the lines of matter formed by said methods or processes, inasmuch as it is my purpose to make the same subjects for still other divisional applications.

Having thus described my invention, what I claim as new is—

1. In a type-forming machine, the combination, with a series of dies, of a plunger for depressing any one of said dies when brought beneath it, die-centering mechanism for centering the dies beneath said plunger, and a type-compression box or matrix, of which the 70 centered and depressed die forms a part, substantially as described.

2. The combination, with the main shaft, of the spring-pressed plunger mounted therein, having a lateral beveled projection, and the 80 actuating cam for operating said plunger, substantially as described.

3. The combination, with the plunger on the main shaft having the lateral projection, of the cam for actuating said plunger and the thimble and spring with which said cam co-operates, substantially as described.

4. The combination, with the plunger on the main shaft having the lateral projection, of the cam for actuating said plunger and the thimble, the spring, and adjusting-nut with which said cam co-operates, substantially as described.

5. In a type forming machine, the combination of a compression-box, a die adapted to form part of the same, means, substantially as described, for feeding a strip of metal or other material to the compression-box, and a plunger operating to cut off a portion of said strip and to compress it in the compression-box to 105 form a type, substantially as described.

6. In a type-forming machine, the combination, with a series of dies arranged in a die-carrier, as described, two independent sliding frames for adjusting the die-carrier in planes 110 at right angles to each other, an arm or plate connected, substantially in the manner described, to each of said sliding frames, a series of setting-pins for actuating each of said movable arms or plates, and two record strips, one 115 for each series of setting-pins, for causing the projection of one or the other of the pins of each series, and thereby, by causing a greater or less movement of the said movable plates or bars, imparting to the slides which operate 120 the die-carrier movements which will bring the desired die to the centering-point, substantially as described.

7. In a type-forming machine, the combination of the sliding carriages on the right and 125 left hand sides of the machine, respectively, the vertically-swinging arms connected to said carriages, the setting-pins, the bell-crank levers, guided and vibrated by the swinging arms, the sliding frames connected to said levers, and the die carrier, substantially as described.

8. In a type-forming machine, the combination of the sliding carriages on the right and

left hand sides of the machine, and each having a series of compartments or shelves, the vertically-swinging arms connected to said carrier, the setting-pins, the bell-crank levers, guided and actuated by the swinging arms, the sliding frames, and the die-carrier, substantially as described.

9. In a type-forming machine, the combination of the sliding carriages on the right and 10 left hand sides of the machine, respectively, the vertically-swinging arms connected to said carriages, the setting-pins, the two record-strips and connections, substantially as described, for projecting the setting-pins in accordance with the scoring of the strips, the 15 bell-crank levers guided and vibrated by the swinging arms, the sliding frames connected to said levers, and the die-carrier, substantially as described.

10. In the herein-described type-forming machine, the combination of the scored record-strip with the feeding-rolls, the contact-bars and contact fingers, the electro-magnets included in circuit with the said contact bars 25 and fingers, the armature-levers operated by said electro-magnets, and the setting-pins connected to said armature-levers, the whole constructed and arranged substantially as described.

11. In the herein-described type-forming machine, the combination of the scored record-strip and its feeding-rollers with the movable arm or plate on the sliding carriage, the tripping-lever and the mechanism connected thereto for rotating the feed-rolls step by step, and the cam on the sliding carriage for actuating said tripping-lever, whereby to cause the record-strip to be advanced after the formation of each character, substantially as described.

12. In a type-forming machine, the combination, substantially as described, with the tripping-lever connected, in the manner substantially as described, to the record-strip feeding mechanism, of the weighted lever, also connected to the tripping lever and adapted to throw the latter into or out of the path of the cam on the sliding carriage, so as to throw the strip-feeding mechanism into or out of operation, as desired, substantially as described.

13. In a type-forming machine, two scored record-strips, two independent series of setting-pins actuated, substantially as described, by said record-strips, and two independent movable arms or frames controlled, respectively, by said two series of setting-pins, in combination with a series of dies, mechanism, substantially as described, operated by the movements of the said two movable arms or frames to center one or the other of the series of dies, a plunger for depressing the centered die, a matrix or mold, of which the centered and depressed die constitutes a part, and a plunger working in the matrix or mold, as set forth.

14. In a type-forming machine, two scored record-strips, two independent series of set-

ting-pins actuated; substantially as described, by said record-strips, and two independent movable arms or frames controlled, respectively, by said two series of setting-pins, in combination with a series of dies, mechanism, substantially as described, operated by the movements of the said two movable arms or frames to center one or the other of the series of dies, a plunger for depressing the centered die, a compression-box with which the centered and depressed die co-operates to form a matrix, devices, substantially as described, for feeding the material of which the type is to be formed to the compression-box, and a plunger operating to sever a portion of the type material, and compress it in the matrix or compression-box against the die, both said plunger and feeding devices being operated from one of the said movable arms or frames, substantially as described, whereby the amount of metal fed to the compression-box and the length of the compressing-plunger are automatically regulated with reference to each other and to the normal thickness of the type, as set forth.

15. In a type-forming machine, the combination, substantially as described, of a series of dies, a die-centering mechanism, a compression-box, means for moving the centered die so as to form part of the compression-box, mechanism, substantially as described, for feeding the type-strip to the compression-box, a cutting-off and compression plunger co-operating with said compression-box, and mechanism, substantially as described, for effecting the feed of the type-strip and regulating the length of said plunger proportioned to the normal width of a type corresponding to the centered die, substantially as described.

16. In a type-forming machine, the combination of a compression-box, a die adapted to form part of the same, and an adjustable plunger operating within said compression-box, substantially as described.

17. In the herein-described type-forming machine, the combination of the cutting and compressing plunger having the screw-threaded shank with the screw-nut connected to said shank, means, substantially as described, for operating the plunger, and means, substantially as described, for rotating the nut so as to lengthen or shorten the plunger, substantially as described.

18. In the herein-described type-forming machine, the combination of the cutting and compressing plunger having the screw-shank, the screw-nut connected thereto, the adjustable connection between said nut and the lever or arm through which said plunger is reciprocated back and forth with said last-mentioned lever, substantially as described.

19. In a type-forming machine, the combination, with a compression-box, a die adapted to form part of the same, and a plunger operating within said compression-box, of a type-throat through which the completed types are discharged from the compression-box having

an adjustable throat-piece, and connections, substantially as described, between the said plunger and throat-piece, whereby a throat-way is formed corresponding to the width of 5 type produced, substantially as described.

20. In the herein-described type-forming machine, the compression-box having the side walls and the upper and lower slides, the former carrying the anvil, in combination with 10 the centered die and the cutting and compressing plunger, substantially as described.

21. In the herein-described type-forming machine, the compression-box having the side walls and the upper and lower slides, the 15 former carrying the anvil, in combination with mechanism, substantially as described, for advancing and retracting the upper slide so as to cause the anvil to free the type from itself and the side walls and bring it in line with the type-throat, and other mechanism, substantially as 20 described, for advancing the lower slide so as to bring its aperture also in line with the type-throat and permit the completed type to drop down through the type-throat, substantially 25 as described.

22. In the herein-described type-forming machine, the combination, with side walls and the upper and lower slides of the compression-box, and mechanisms, substantially as 30 described, for operating said slides, of the type-throat having a movable throat-piece and mechanism, substantially as described, for adjusting said throat-piece, as set forth.

23. In the herein-described type-forming machine, the combination, with the compression-box or matrix in which the types are formed, of the reciprocating cutting and compressing plunger and the positively-acting feeding-rolls for feeding the type strip to the 35 compression-box transversely of the plunger, substantially as described.

24. In a type-forming machine, a series of dies, mechanism for centering any one of said dies, a compression-box or matrix of which 40 the centered die is adapted to form a part, a reciprocating plunger operating to cut off a portion from a type-strip and to compress it within the compression-box or matrix, mechanism, substantially as described, for imparting to the said plunger movements that will effect the production of types of normal size, and independent mechanism, substantially as 45 described, set in operation by a record-strip, for shortening the plunger, so as to cause it to make types of greater width or space value, such as will produce justified lines, substantially as described.

25. In a type-forming machine, the combination of two series of setting-pins, two movable arms or frames controlled thereby, a die-carrier having a series of dies arranged therein, connections, substantially as described, between the movable arms or frames and the die-carrier, by which the die is centered, a compression-box or matrix of which the centered 55 die forms a part, a reciprocating plunger operating within the compression-box or matrix,

means, substantially such as described, for adjusting the length of the plunger, connections, substantially as described, between said adjusting means and one of the swinging arms, and two record-strips, both of which are scored in a manner to set in operation both series of setting-pins and effect the centering of any particular die, and one of which is further 70 scored in a manner to independently set in operation one series of setting-pins, and thus, by effecting the throw of the movable arm or frame which controls the plunger-adjusting mechanism, cause the plunger to be shortened 75 and effect the production of types of a width or space value greater than normal, as set forth.

26. In a type-forming machine, the combination of two series of setting-pins, two movable arms or frames controlled thereby, a die-carrier having a series of dies arranged therein, connections, substantially as described, between the movable arms or frames and the die-carrier, a compression-box or matrix of 80 which the centered die forms a part, a plunger operating within the compression-box, means, substantially such as described, for adjusting the length of the plunger, a type-throat having an adjustable wall, connections, substantially 85 as described, between said plunger, adjusting means, and the adjustable type-throat wall and one of the swinging arms and two record-strips, both of which are scored in a manner to set in operation both swinging arms, and one of which 90 is further scored so as to independently set in operation the series of setting-pins which controls the movement of the arm with which the plunger-adjusting devices and the type-throat wall are connected, substantially as described. 95

27. The combination, with the setting-pins and the vertically-movable arm or plate mounted on the sliding carriage on the right-hand side of the machine and controlled by the setting-pins, of the rod connected to said movable arm, and the arm or lever to which said connecting-rod is jointed, the rock-shaft to which said arm or lever is secured, and the cutting and compressing plunger of the type-forming mechanism, operated from said rock-shaft, substantially as described. 100

28. The combination, with the setting-pins, the vertically-movable arm or plate mounted on the sliding carriage on the right-hand side of the machine and controlled by the setting-pins, of the rod connected to said movable arm, the arm or lever to which said connecting-rod is jointed, the rock-shaft to which said arm or lever is secured, the rolls for feeding the type-strip, and the intermediate connections, whereby the said feed-rolls are caused to advance the type-strip to the compression-box more or less, according to the amount of motion imparted to said rock-shaft, substantially as described. 115

29. The combination, with the setting-pins, the vertically-movable arm or plate mounted on the sliding carriage on the right-hand side of the machine, and controlled by the setting- 120

pins, as described, of the rod connected to said movable arm and the arm or lever to which said connecting-rod is jointed, the rock-shaft to which said arm or lever is secured, the cutting compressing-plunger, and the type-strip-feeding rolls, and intermediate connections, such as set forth, between said rock-shaft and the said plunger and feeding-rolls, substantially as described.

30. The combination, with the vertically-movable arm or plate mounted upon the sliding carriage on the right-hand side of the machine, of the movable throat-piece forming part of the discharge-throat for the type, and intermediate connections, substantially such as described, between the said vertically-movable arm and such throat-piece, substantially as described.

31. The combination of the adjustable cutting and compressing plunger and the adjustable throat-piece with the vertically-movable arm or plate mounted on the carriage on the right-hand side of the machine, and connections, substantially as described, between such vertically-moving arm and the said adjustable plunger and movable throat-piece, substantially as described.

32. The combination of the type-strip-feeding devices and the adjustable throat-piece with the vertically-movable arm or plate mounted on the sliding carriage on the right-hand side of the machine, and the intermediate connections, substantially such as described, by which said strip-feeding devices and the said movable throat-piece are operated from the said vertically-movable arm or plate, substantially as described.

33. The combination of the adjustable cutting and compressing plunger, the type-strip-feeding devices, and the adjustable type-throat with the vertically-movable arm or plate mounted on the right-hand side of the machine, and the intermediate connections, substantially such as described, by which said adjustable plunger, type-strip-feeding mechanism, and adjustable throat are operated from said vertically-movable arm or plate, substantially as described.

34. In a type-forming machine, the combination, with the type-forming matrix of which a die forms a part, of a reciprocating plunger operating in said matrix, mechanism, substantially such as described, for lengthening or shortening the plunger, so as to regulate the extent of its movement within the matrix, a series of setting-pins, a movable arm or frame controlled thereby, connections, substantially as described, between said arm or frame and the mechanism for lengthening and shortening the plunger, and a scored record-strip for co-operating with and actuating setting-pins, whereby, by means of the scoring of the record-strip, the movement of the plunger within the matrix and the width or space value of the type formed is regulated, substantially as described.

35. In the herein-described type-forming machine, the combination, with the adjustable type-forming devices, the vertically-movable arm or plate on the right-hand side of the machine, and the adjustable connections, substantially such as described, between said vertically-movable arm and the type-forming devices, by means of which a given throw of said movable arm may be caused to impart more or less movement to the type-forming mechanism, of the vertically-movable arm or plate on the left-hand side of the machine, and mechanism, substantially such as described, set in operation by said last-named movable arm, for adjusting the said adjustable connections on the right-hand side of the machine, so as to cause the types produced to be of the width or space value, more or less, above the normal, substantially as described.

36. In the herein-described type-forming machine, the combination, with the adjustable type-forming devices, and the adjustable connections between said type-forming devices and the vertically-movable arm or plate on the right-hand side of the machine, by which the said die-forming devices are operated, of a justifying-bar, means, substantially such as described, for shifting it vertically by the operation of the vertically-movable arm on the left-hand side of the machine, and devices, substantially such as described, operated by the shifting of said justifying-bar, for setting the adjustable connections referred to on the right-hand side of the machine, for the purpose specified.

37. In the herein-described type-forming machine, the combination, with the vertically-movable shaft on the left-hand or justifying side of the machine, and means, substantially such as described, for turning it, of the vertically-sliding justifying-bar, devices, substantially such as described, for connecting said shaft to said justifying-bar and causing the latter to be raised, and a bar, shifted by the movement of the justifying-bar, for setting the adjustable connections on the right-hand side of the machine, substantially as described.

38. In the herein-described type-forming machine, the combination, with the vertically-movable shaft on the left-hand or justifying side of the machine, and the vertically-sliding justifying-bar which said shaft lifts, of the spring-projected pawl for engaging said justifying-bar and holding it in the elevated position during the formation of the types for a line, substantially as described.

39. In the herein-described type-forming machine, the combination, with the vertically-adjustable shaft on the left-hand or justifying side of the machine and the justifying-bar, of the spring-pawl for engaging with the justifying-bar and the projection and hook on the shaft co-operating, respectively, with the spring-pawl and a hook on the justifying-bar, whereby when the shaft is turned in one direction it will engage its hook with the hook

on the justifying-bar and will disengage the spring-pawl from the latter, and vice versa, substantially as described.

40. The combination, with the justifying-bar having the shoulders arranged progressively on its edge, with the arm on the vertically-movable shaft for co-operating with said shoulders, of the connecting rod and pin with which the vertical edge of said justifying-bar co-operates, and the described mechanism on the right-hand side of the machine operated upon by said connecting-rod, substantially as described.

41. The combination of the two vertically-movable justifying-bars, the adjustable pin adapted to be shifted so as to engage with either of said bars, the connecting-rod upon which said pin is mounted, and the described mechanism on the right-hand side of the machine operated upon by said connecting-rod, substantially as described.

42. In the herein-described type-forming machine the combination, of the springs in the lower end of the type-throat, the movable throat-piece, and the plunger for causing the advance of the throat-piece and the consequent transfer of the type from the throat-piece to the galley, substantially as described.

43. In the herein-described type-forming machine, the combination, with the galley, of the laterally-movable bars thereon, which retreat as the types are assembled, substantially as described.

44. In the herein-described type-forming machine, the combination, with the galley, of the bars which retreat as the types are assembled and steel "leads" or thin line spaces, substantially as described.

45. In the herein-described type-forming machine, the combination, with the galley bearing its retreating-bars, of the stop on the frame for arresting the movement of the types as each line becomes filled, whereby the types are properly held after the follower-bar is pushed out of the way, substantially as described.

46. In the herein-described type-forming machine, the galleys provided at opposite ends with shoulders or pins and adapted to fit into each other and preserve practically smooth joints, substantially as described.

47. In a type-forming machine, the combi-

nation of a matrix or compression-box in which the types are formed, an adjustable plunger working within said box and determining by the extent of its movement the width of the type produced, means, substantially as described, for adjusting the plunger before commencing the types for a line, a movable galley, and means, substantially such as described, for transferring the completed type to said galley, and devices, substantially such as described, operated upon by the mechanism which adjusts the throw of the plunger, for automatically advancing the galley, whereby as the machine is set for the production of a new line of types the galley will be automatically advanced in position to receive the types for said new line, substantially as described.

48. In a type-forming machine, the combination of the galley, a mechanism, substantially such as described, for advancing the galley step by step, and the movable justifying-bar on the left-hand side of the machine for imparting motion to said step-by-step mechanism.

49. In a type-forming machine, the combination, with the galley having the racks, of the vibratory pawls, the rock-shaft and its arm, and the movable justifying-bar and its connection for vibrating said rock-shaft, substantially as described.

50. In a type-forming machine, the combination, with the galley, of the movable justifying-bar adapted to be set before the formation of types for a new line, as described, a feeding mechanism, substantially such as described, between the justifying-bar and the galley, for advancing the galley as the justifying-bar is shifted, and devices for arresting the said galley when it has advanced the distance of one line, substantially as described.

51. In the herein-described type-forming machine, the combination of the arm L^1 , containing a spring-projected dog or pawl, with the pivoted arm L^6 , stationary arm L^8 , and pawl L^9 , and the reversed ratchet-bars on the galley, the whole constructed and arranged substantially as described.
